RING TOSS TOY

Lee Triplett, Salt Lake City, Utah, assignor to Expando Products Company, Magna, Utah

Continuation of design application Ser. No. 12,916, July 26, 1968. This application Dec. 22, 1969, Ser. No. 20,608

Term of patent 14 years

Int. Cl. D21—02

U.S. Cl. D34—5

FIG. 1

FIG. 2

FIG. 1 is a plan view of the ring toss toy or similar article; the reverse side of the ring toss toy or similar article is identical.

FIG. 2 is a transverse vertical section taken along the line 2—2.

This is a continuation of design application D. 12,916, filed Dec. 22, 1969, now abandoned.

I claim:

The ornamental design for a ring toss toy, substantially as shown and described.
